INVENTOR

UNITED STATES PATENT OFFICE

119,026

DESIGN FOR A TEXTILE FABRIC

James R. Jowett, Philadelphia, Pa.

Application December 1, 1939, Serial No. 88,607

Term of patent 3½ years

To all whom it may concern:

Be it known that I, James R. Jowett, a citizen of the United States residing at Philadelphia, in the county of Philadelphia and State of Pennsylvania, have invented a new, original, and ornamental Design for a Textile Fabric, of which the following is a specification, reference being had to the accompanying drawing, forming part thereof.

The figure is a plan view of a textile fabric embodying my design.

I claim:

The ornamental design for a textile fabric, as shown.

JAMES R. JOWETT.
